(No Model.)

C. M. JOSLIN.
SPRING AIR GUN.

No. 439,246.

Patented Oct. 28, 1890.

UNITED STATES PATENT OFFICE.

CHARLES M. JOSLIN, OF NORTHLAKE, MICHIGAN.

SPRING AIR-GUN.

SPECIFICATION forming part of Letters Patent No. 439,246, dated October 28, 1890.

Application filed March 24, 1890. Serial No. 345,041. (No model.)

To all whom it may concern:

Be it known that I, CHARLES M. JOSLIN, a citizen of the United States, residing at Northville, county of Wayne, State of Michigan, have invented a certain new and useful Improvement in Air-Guns; and I declare the following to be a full, clear, and exact description of the same, such as will enable others skilled in the art to which it appertains to make and use the same, reference being had to the accompanying drawings, which form a part of this specification.

My invention relates to new and useful improvements in air-guns; and it consists of the devices and appliances, with their combinations and arrangements, as herein specified and claimed, and more fully illustrated in the accompanying drawings, in which—

Figure 1 is a side elevation. Fig. 2 is a longitudinal vertical section. Fig. 3 is a plan view with the cap removed. Fig. 4 is a vertical cross-section on the line $x-x$, Fig. 2. Fig. 5 is a similar section on the line $y-y$, Fig. 2; and Fig. 6 is a similar view on the line $z-z$, Fig. 2.

The object of my invention is to provide an air-gun of simple, durable, and efficient construction, and which shall be capable of being manufactured so economically as to be re-tailed at a very low figure. To these ends I carry out my invention as follows:

A represents the stock, provided with breech A' and barrel A'', made of wood, the barrel having a removable cover or cap A³.

B denotes a metal air-chamber provided with a metal barrel B' communicating therewith.

C denotes the plunger, constructed with the usual reciprocating head C' and stem C''.

D is the spring to retract the plunger to compress the air in the air-chamber.

E is a locking-arm engaged upon the stem of the plunger, and F a return-rod sleeved through said arm. This rod may simply be bent at its forward end, as shown at f, to prevent its disengagement with the locking-arm. So, also, the rear end is bent, as shown at f', to engage the operating-lever. G denotes said lever, which I prefer to construct with a laterally-extended arm G', provided with a perforated shoulder G² to engage the return-rod. The rear of the lever is also down-

wardly extended, as shown at G³, through which the lever is fulcrumed upon the stock A, preferably by a bolt G⁴, provided with a nut thereupon to hold the lever firmly in place and in a durable manner, effectually withstanding all strain thereon. The portion G³ of said lever may extend downward along the outside of the stock, as shown in Fig. 1, or it may extend downward through or into a recess in the stock in the rear of the barrel, as shown in Fig. 2. The lever is so constructed and arranged as to lie down along the side of the barrel when in normal position, as shown.

H is the trigger, the detent h whereof engages the lower end of the locking-arm E when the spring has been compressed.

To locate the air-chamber B, with its barrel B' and spring-actuated plunger C, in place in the wooden stock, the wooden barrel is recessed intermediate its ends, as shown at a, to receive the air-chamber, and along the forward end, as shown at a', to receive the metal barrel, and also along the rear end, as shown at a'', to receive the spring-actuated plunger, return-rod, and connected parts adjacent thereto. When the said chamber and metal barrel are in place, I prefer to close the recess a' above the metal barrel with a strip a³. Over all the cap A³ is then engaged, as by screws A⁴, holding the air-chamber and related parts in place and closing the stock, although the cap is not essential, as the gun would work efficiently without it. It will be observed that by so recessing the wooden barrel to receive the air-chamber the wooden barrel abuts firmly against both ends of the air-chamber, as shown at a⁴ and a⁵, holding the chamber securely against all longitudinal strain.

The return-rod F is constructed of a straight piece of wire bent at its extremities and reciprocating through the locking-arm.

The air-chamber, metal barrel, spring-actuated plunger, and return-rod are all readily removable from the stock A, if desired, by simply removing the cap A³.

What I claim as my invention is—

1. In an air-gun, the combination, with the wooden barrel constructed with recesses a a' a'', of a metal air-chamber provided with an integral barrel and reciprocating plunger and a strip to inclose the recess a' and a strip or

cap to inclose the recesses α and α^2 , said strip or cap also overlying the first-named strip.

2. In an air-gun, the combination, with the barrel and breech, of an air-chamber provided with a spring-actuated plunger, a locking-arm engaged upon the stem of the plunger, a return-rod for retracting said arm, and an operating-lever constructed with a laterally-projecting arm to connect with the plunger.
3. In an air-gun, the combination, with a wooden barrel and breech, of a separable air-chamber provided with a spring-actuated plunger, a locking-arm engaged upon the stem of the plunger, and a return-rod sleeved through said arm, substantially as set forth.
4. In an air-gun, the combination, with the spring-actuated plunger, of an operating-lever fulcrumed to the stock of the gun, said lever constructed with a laterally-extended

arm to connect with the plunger, the forward end of said lever in its normal position lying adjacent to the side of the stock of the gun, substantially as set forth.

5. In an air-gun, the combination, with a spring-actuated plunger provided with a locking-arm and a return-rod engaged therewith, of an operating-lever constructed with a laterally-extended arm connected with said rod, said lever fulcrumed at its rear end to the stock of the gun, its forward end in its normal position lying at the side of the stock, substantially as set forth.

In testimony whereof I sign this specification in the presence of two witnesses.

CHARLES M. JOSLIN.
